UNITED STATES PATENT OFFICE.

THOMAS J. SHEPHERD, OF RAINY, OKLAHOMA TERRITORY.

DESIGN FOR A CABINET.

SPECIFICATION forming part of Design No. 24,475, dated July 16, 1895.

Application filed May 22, 1895. Serial No. 550,270. Term of patent 3½ years.

To all whom it may concern:

Be it known that I, THOMAS J. SHEPHERD, of Rainey, in the county of Washita, Oklahoma Territory, have invented a certain new and useful Design for Cabinets; and I do hereby declare the following to be a full, clear, and exact description of the invention, such as will enable others skilled in the art to which it pertains to make and use it, reference being had to the accompanying drawing, which forms part of this specification.

My invention relates to improvements in designs for cabinets, which are fully illustrated in the accompanying drawing, which is 15 a perspective view thereof.

The characteristic features of my design consist of the lower rectangular portion A with the slightly-projecting top B, and the rectangular compartment or cupboard C situated in 20 the center of the top B, and the small rectan-

gular compartments D at each side of the center cupboard C.

One of the compartments D is provided with vertical doors and the other is divided into several compartments, as illustrated. 25

The lower portion A has a representation of doors and drawers in the relation there illustrated.

Having thus described my invention, what I claim, and desire to secure by Letters Patent, is—

The design for a cabinet, substantially as herein shown and described.

In testimony whereof I affix my signature in presence of two witnesses.

THOMAS J. SHEPHERD.
